UNITED STATES PATENT OFFICE

90,633

DESIGN FOR A DISPENSING FAUCET

Franklin G. Slagel, Buffalo, N. Y., assignor to
Fedders Manufacturing Company, Inc., Buffalo, N. Y.

Application January 4, 1933. Serial No. 46,732

Term of patent 14 years

To all whom it may concern:

Be it known that I, FRANKLIN G. SLAGEL, a citizen of the United States, residing at Buffalo, in the county of Erie and State of New York, have invented a new, original, and ornamental Design for a Dispensing Faucet, of which the following is a specification, reference being had to the accompanying drawing, forming a part thereof.

In the drawing:

Fig. 1 is a front elevation of the dispensing faucet showing my new design.

Fig. 2 is a side elevation thereof.

I claim:

The ornamental design for a dispensing faucet, substantially as shown.

FRANKLIN G. SLAGEL.
